(57) **CLAIM**

The ornamental design for a chair with support and beanbag cushion as shown and described.

DESCRIPTION

FIG. 1 is a front perspective view of the chair with support and beanbag cushion;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a back view; and,

FIG. 8 is a front perspective view thereof, showing the article in use with environmental subject matter.

The broken lines shown in the drawings depict environmental subject matter that forms no part of the claimed design.

1 Claim, 6 Drawing Sheets
